(57) **CLAIM**

The ornamental design for a black clamshell trunking, as shown and described.

DESCRIPTION

FIG. 1 is a perspective view of a black clamshell trunking, showing the new design;

FIG. 2 is a front view thereof;

FIG. 3 is a rear view thereof;

FIG. 4 is a left-side view thereof;

FIG. 5 is a right-side view thereof;

FIG. 6 is a top view thereof; and

FIG. 7 is a bottom view thereof; and,

FIG. 8 is another perspective view thereof, shown in an open state.

The black clamshell trunking is broken away to indicate that no particular length is claimed.
